UNITED STATES PATENT OFFICE

148,957

DESIGN FOR A COMBINATION TOOL

Lee Rice, Homeland, Fla.

Application September 6, 1946, Serial No. 133,105

Term of patent 14 years

(Cl. D44—29)

To all whom it may concern:

Be it known that I, Lee Rice, a citizen of the United States, residing at Homeland, in the county of Polk and State of Florida, have invented a new, original, and ornamental Design for a Combination Tool, of which the following is a specification, reference being had to the accompanying drawing, forming a part thereof.

Figure 1 is a face view of a combination tool, showing my new design.

Figure 2 is an edge view of the same.

I claim:

The ornamental design for a combination tool, as shown.

LEE RICE.
